(57) **CLAIM**

The ornamental design for a ladder light, as shown and described.

DESCRIPTION

FIG. 1 is a front, right and top perspective view of a ladder light, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is a front, right and top perspective view of a ladder light in FIG. 1 without the top piece.

FIG. 12 is a rear, left and bottom perspective view of FIG. 11.

FIG. 13 is a front elevation view of FIG. 11.

FIG. 14 is a rear elevation view of FIG. 11.

FIG. 15 is a left side elevation view of FIG. 11.

FIG. 16 is a right side elevation view of FIG. 11.

FIG. 17 is a top plan view of FIG. 11.

FIG. 18 is a bottom plan view of FIG. 11.

FIG. 19 is an enlarged view of detail 19 in FIG. 11.

FIG. 20 is an enlarged view of detail 20 in FIG. 11.

FIG. 21 is another front, right and top perspective view of the ladder light shown in FIG. 11 in an alternate configuration of use.

FIG. 22 is another front, right and top perspective view of the ladder light shown in FIG. 11 in an alternate configuration of use.

FIG. 23 is another front, right and top perspective view of the ladder light shown in FIG. 11 in an alternate configuration of use; and,

(Continued)

FIG. 24 is another front, right and top perspective view of the ladder light shown in FIG. 11 in an alternate configuration of use.

The broken lines depict portions of the Ladder Light that form no part of the claimed design. The dot-dash broken lines in FIGS. 1, 9, 10, 11, 19 and 20 depict the boundaries of the enlargements that form no part of the claimed design.
